ELECTRODYNAMIC TRANSMITTER

Carl Albert Hartmann, Berlin-Siemensstadt,
Germany, assignor to Siemens & Halske, Aktiengesellschaft, Siemensstadt, near Berlin,
Germany, a corporation of Germany

Application August 20, 1931, Serial No. 558,314
In Germany August 21, 1930

9 Claims. (Cl. 179—121)

The invention relates to electro-dynamic transmitters having diaphragms traversed by current, and is more particularly concerned with ribbon transmitters.

5 In the constructional design of ribbon transmitters, the entire chamber behind the ribbon up to the immediate neighbourhood thereof is filled with a felt packing. The operation of such a device is as follows: At low frequencies, only 10 the resonance of the ribbon whose peak lies at about 100—200 cycles is noticeable; in the range of intermediate frequencies, the resonance of the chamber coupled to the ribbon is also manifest. As to its situation and selectivity, it depends on 15 the felt packing and, furthermore, on the way in which the chamber is connected to the outer air. The ribbon transmitters developed in this manner meet, in general, all the requirements involved in satisfactory transmission. However, 20 they have the disadvantages of low sensitivity for high frequencies, and of causing noticeable variations in the reproduction of the intermediate frequencies in the case of different transmitters, the latter being due to the variations in the felt packings of such transmitters. It is, therefore, 25 difficult to produce in quantities transmitters having similar characteristics. However, quantity production is desirable for technical purposes and for reasons of economy.

30 According to the invention, these drawbacks can be avoided and the reproduction of frequencies, particularly the high frequencies, can be improved by placing one or several resonators behind the ribbon. Use should preferably be 35 made of a well-defined chamber behind the ribbon as a resonator. Together with the ribbon mass, it is designed to provide for a natural oscillation (transverse resonance) in the high frequency range, for instance at 400 cycles.

40 By means of this resonance the reproduction of high frequencies is materially improved, whereas without this chamber, the frequency characteristics would slope down considerably. A further improvement—for the highest frequencies—is obtained by means of the longitudinal resonance (singing effect) of the chamber. The 45 natural oscillation of the longitudinal resonance is caused to lie at about 8000 cycles. It is the fundamental frequency of the chamber behind the ribbon which is open at both ends (top and bottom). The fact that the chamber is open at its ends does not impair the production of transverse resonance, since the pressure conditions behind the ribbon centre at the transverse res-

onance frequency are no longer acted on appreciably by the end conditions, provided the transverse resonance frequency is sufficiently high.

The reduction of the chamber behind the ribbon would considerably reduce the ribbon amplitude outside the resonance range, owing to the stiffness of the air-cushion. According to the invention, the remainder of the previous large chamber at the back, and embraced by the magnet-legs, is therefore coupled to the chamber behind the ribbon, with the result that its resonance is again set up in the intermediate frequency range. In order to obtain the transverse resonance nevertheless in the small chamber, the coupling is, for instance, effected through a slot. 5 This slot is so dimensioned that, already somewhat below the resonance frequency of the small chamber, its damping is sufficiently high to prevent appreciable sound energies from entering the large chamber. At high frequencies, the air remains, so to speak, within the slot. This practically means an automatic coupling of the large chamber at high frequencies. For the range of intermediate frequencies, however,—the resonance range of the large chamber,—the slot 10 damping must be negligibly low. 15

20 Instead of the slot, provision may also be made for narrow holes or the like, which present the resistance required for high frequencies.

25 The drawings show a constructional example 30 of the object of the invention.

Fig. 1 shows a cross-sectional view of the transmitter; Fig. 2 a section in the direction A—B of Fig. 1. Fig. 3 is a performance curve of the 35 transmitter.

In the air-gap of the magnet 7, there is arranged a ribbon 2 and behind it the chamber or resonator 1, which is in connection with the chamber or resonator 3 through the slot 4. The large chamber 3 is packed with felt in a well-known manner; the resonator 1 is connected with the outer air through gauze-covered apertures 6. Wider slots 5 connect also the resonator 3 with the outside air. 40

45 The various resonance frequencies must be chosen so as to avoid spaces in the frequency characteristics. This condition is fulfilled if the various resonators are strongly damped. The damping is obtained for the large chamber 3 by means of a felt packing applied in a well-known manner. In addition, the damping is increased by the apertures 5 through which the chamber 3 is connected with the outside air. The same holds 50 true for the small chamber 1 which is kept in 55

touch with the outside air by means of the gauze windows 6. The energy delivered to the coupling slot 4 further increases the damping of the small chamber 1.

- 5 The performance of the new ribbon transmitter, with respect to the different frequencies of the incident sound, will be explained with reference to Fig. 3. For the lowest frequencies, it is the natural oscillation of the ribbon (curve 1) 10 which is decisive. It is very soon superimposed for intermediate frequencies by the resonance frequency of the large chamber (curve 2). In proportion as the frequency is further increased, the slot effect of the large chamber is stopped, 15 the transverse resonance of the small chamber (curve 3) becomes effective and prevents a reduction in sensitivity (curve 4).

The new structure provides a wider frequency band and the possibility of manufacturing uniform apparatus. Even though in the range of intermediate frequencies the influence of the felt packing is noticeable, the well-defined resonator 1 in the immediate neighbourhood of the ribbon and its disconnection by means of the slot avoids 20 the action of the felt at the higher frequencies. The frequency characteristic of the transmitter varies if it is used in another atmosphere, say within a hydrogen-atmosphere, which may sometimes be recommendable. The transverse resonance does not vary if another medium is chosen, 25 whereas the longitudinal resonance, as a function of the sound velocity in the medium involved, is subject to considerable variations.

I claim.

- 30 1. In a transmitter of the class described, a magnet, a conductive ribbon disposed between the poles of said magnet and adapted to carry alternating currents of frequencies within the audible range, said ribbon having a natural frequency of about 30 to 200 cycles, a high frequency resonator disposed adjacent said ribbon, said resonator having two resonance frequencies, one of them being about 4000 cycles and the other about 8000 cycles, an intermediate frequency 35 resonator disposed in series connection with said high frequency resonator, the natural frequency of said intermediate frequency resonator being about 300 to 800 cycles, passages for making said series connection, said passages preventing the 40 passing of high frequencies, apertures connecting with the exterior for damping said high frequency resonator and sound impeding means for damping said intermediate frequency resonator.

2. An electro-dynamic transmitter comprising, 45 a magnet, a conductive ribbon disposed between the poles of said magnet and adapted to carry alternating current frequencies within the audible range, the natural frequency of said ribbon being less than 200 cycles, means forming a high frequency resonator adjacent said ribbon, means forming an intermediate frequency resonator adjacent said high frequency resonator, passages in said first means for connecting said resonators in series, said passages being impervious to high 50 frequencies apertures for damping said high frequency resonator, and sound impeding means for damping said intermediate frequency resonator.

- 55 3. An electro-dynamic transmitter of the class described comprising, a magnet, a conductive ribbon disposed between the poles of said magnet, means forming a high frequency resonator adjacent said ribbon, an intermediate frequency resonator disposed adjacent said high frequency

resonator, the natural frequencies of said resonators differing by more than one octave, passages in said means impervious to high frequencies for connecting said resonators in series, apertures in said means opening to the exterior for damping 5 said high frequency resonator, and sound impeding means for damping said intermediate frequency resonator.

4. In an electro-dynamic transmitter having a yieldable conductive ribbon and a plurality of 10 relatively highly damped serially connected resonators, an air chamber in back of said ribbon toward and from which said ribbon can freely oscillate, the natural frequency of said air chamber being within the range of high frequencies, 15 and an aperture in the wall of said air chamber for damping the same.

5. An electro-dynamic transmitter of the class described comprising, a yieldable conductive ribbon, an air chamber in back of said ribbon toward and from which said ribbon can freely oscillate, an aperture in the wall of said air chamber for damping same, said air chamber having 20 two resonance frequencies, one at about 4000 cycles and the other at about 8000 cycles. 25

6. In an electro-dynamic transmitter of the class described having a plurality of serially connected resonators and a yieldable conductive ribbon, an air chamber in back of said ribbon toward and from which said ribbon can freely 30 oscillate, said air chamber forming a resonator the natural frequency of which is within the range of high frequencies, and an opening in the wall of said air chamber so dimensioned as to 35 impede the passage of high frequencies there-through.

7. In a transmitter of the class described arranged to cover a large range of frequencies and including a plurality of vibratory structures each of a different natural frequency coupled with one 40 another in series relation, a yieldable conductive ribbon, an auxiliary resonator in back of said ribbon comprising means forming an air chamber toward and from which said ribbon can freely oscillate, the natural frequency of said air chamber 45 being in the range of high frequencies, and an opening in said means which is impervious to high frequencies for establishing series relation with another vibratory structure.

8. An electro-dynamic transmitter comprising, 50 a conductive ribbon disposed between the poles of a magnet, the natural frequency of said ribbon being within the low frequency range, an air chamber in back of said ribbon, the natural frequency of said chamber being in the range of 55 high frequencies, an opening in the wall forming said chamber, said opening being impervious to high frequencies, and additional resonance chamber means arranged in series relation behind said ribbon and said first chamber, said last named 60 means being tuned to a natural frequency different from the others.

9. An electro dynamic transmitter comprising a conductive ribbon disposed between the poles of a magnet, a plurality of relatively highly 65 damped vibratory structures each tuned to a natural frequency different from the other disposed in back of said ribbon and serially related thereto, coupling means intermediate of said structures arranged to maintain said series relation therebetween, said coupling means comprising a member having an aperture which is substantially impervious to high frequencies.
